his Attorney.

UNITED STATES PATENT OFFICE.

GEORGE WILLARD DOUGLAS, OF SAN FRANCISCO, CALIFORNIA, ASSIGNOR
TO THE MARKET STREET RAILWAY COMPANY, OF SAME PLACE.

CAR-FENDER.

SPECIFICATION forming part of Letters Patent No. 601,242, dated March 29, 1898.

Application filed November 29, 1897. Serial No. 660,126. (No model.)

To all whom it may concern:

Be it known that I, GEORGE WILLARD DOUGLAS, a citizen of the United States, residing in the city and county of San Francisco 5 and State of California, have invented certain new and useful Improvements in Car-Fenders; and I do hereby declare the following to be a full, clear, and exact description of the same.

10 My invention relates to that class of car-fenders or safety-guards for cars in which the fender proper is carried normally above the road-bed in a safe but substantially inoperative position and is thrown into action either 15 automatically by the contact of the obstructing body with a trigger-guard in front or intentionally by the operation by the motor-man or gripman of suitable levers, whereby the carrying or holding devices of the fender 20 are tripped and said fender is permitted to move down into position to receive the body and prevent it, either by picking it up or by rolling it off, from getting under the wheels.

The object of my invention is to provide a 25 fender of this class of such simple construction that it will not get out of order, but yet shall be effective in operation and generally shall answer all the varied conditions of car construction and travel; and with these ends 30 in view my invention consists in the novel construction and arrangement of the fender, the trigger-guard, and the intervening holding and tripping mechanism, which I shall hereinafter fully describe by reference to the 35 accompanying drawings, in which—

Figure 1 is a plan of my fender; and Fig. 2 is a vertical longitudinal section of same on line $\alpha\alpha$ of Fig. 1, showing also the car floor and frame.

40 A is a portion of the car floor and frame, and B is one of the fixed beams of the truck, the remainder of which need not be herein shown.

C is the fender proper or apron. It may be 45 constructed in various ways; but I deem the best form that here shown—namely, a series of spring-steel rods bent as in Fig. 2, their lower extremities carrying cushion-rollers c, and the whole forming a kind of scoop extending 50 transversely over the road-bed. The upper

ends of these rods are secured to a head c', to which are pivoted at c² the carrying-arms c³, which extend backwardly and downwardly and are secured to a cross-plate c⁴, which at its lower back edge and near each end is 55 hinged to a bracket b, secured to truck-beam B, said hinge being shown at b'. Braces c⁵ strengthen arms c³.

The apron or fender C, notwithstanding its pivotal connection at c² with arms c³, is held 60 in normal position by springs c⁶, seated between the plate c⁴ and a cross-bar c⁷ on the backs of the apron-rods, and these springs so hold the apron that its foot is carried normally high enough above the road-bed to be 65 perfectly safe from injury. At the same time contact with the foot of the apron will force it down to the road-bed, in which movement it turns about its hinges at c², pressing backwardly against its springs c⁶. The apron has, 70 however, a more positive action than this—namely, one by which it is enabled to drop its foot down to the road-bed prior to any contact and in preparation therefor. This movement is effected about its hinge connection 75 at b'.

The whole apron is held up in its normal position by means of a rearwardly-extending arm D, projecting from the top of cross-plate c⁴ and braced thereto by a rod d. This arm 80 has a downturned rear extremity d'.

Pivoted to a bracket b² of truck-beam B is a trigger-lever E, controlled by a spring e and having secured to it a pin e', which projects directly over the arm D and finds a seat 85 against a shoulder d² on said arm. Now as long as this trigger-lever E, under the control of its spring e, is held forward to its seat the cross-pin e' bears upon and holds down the arm D, which, unable to rise as it would have to do 90 if the plate c⁴ turned about hinge b', thereby holds said plate up, and thus carries the whole fender or apron in its normally inactive position; but if the trigger-lever E be pushed back, so as to cause its pin e' to free 95 the arm D, the whole fender will turn about hinge b' and the foot of the apron will fall to the road-bed ready to receive and pick up or roll off an obstructing body. This tripping effect may be, as is usual in this class of fen- 100

ders, accomplished both automatically and by intention, or by either method. I have here shown both.

F is a trigger-guard hinged at its upper end under the car in advance of the fender proper. From this guard a rod f extends rearwardly to and is connected with the trigger-lever E. An obstructing body coming in contact with the trigger-guard F will force it back, and thus cause the trigger-lever E to be forced back, with the result of dropping the fender, as previously explained. When thus dropped, the fender cannot be forced up again by the obstructing body, both by reason of the inherent construction of the apron, the steel rods of which tend to be forced down rather than up, and also by reason of the downturned end d' of arm D bearing against the cross-pin e', and thus preventing movement about hinge b'.

The foot-trip to be operated by the motor-man or gripman, if he have time, consists of a treadle or foot-piece G, extending up through the car-floor and adapted to rock a shaft g, a crank g' of which is let into the connecting-rod f.

Having thus described my invention, what I claim as new, and desire to secure by Letters Patent, is—

30 1. A car-fender comprising an apron the foot of which is carried normally above the road-bed, a cross-plate hinged to the truck-frame and to which the apron is connected, an arm secured to said cross-plate, in position to control its hinge and hold the apron up in its normal position, and means for holding said arm to maintain the apron in said position, and releasing said arm to drop said apron with its foot resting on the road-bed, 40 and means for yieldingly retaining said holding means in active position.

2. A car-fender comprising an apron the foot of which is carried normally above the road-bed, a cross-plate hinged to the truck-frame and to which the apron is connected, an arm secured to said cross-plate in position to control its hinge, a trigger-lever hinged to the truck-frame and having a pin bearing above said arm to hold it down, and means 45 for swinging the trigger-lever to cause its pin to release the arm, whereby the apron may drop to rest its foot upon the roadway.

3. A car-fender comprising an apron the foot of which is carried normally above the road-bed, a cross-plate hinged to the truck-frame and to which the apron is connected, an arm secured to said cross-plate in position to control its hinge, said arm having a downturned rear end, a spring-controlled trigger-lever hinged to the truck-frame and having a pin bearing above said arm and seated normally against a shoulder thereon, whereby the apron is held up in normal position, and means for swinging the trigger-lever 60 to carry its pin free of the arm which is thereby released and rises with its downturned rear end bearing against the pin, whereby

the apron is dropped to rest its foot on the road-bed and is there held.

4. A car-fender comprising an apron the 70 foot of which is carried normally above the road-bed, a cross-plate hinged to the truck-frame and to which the apron is connected, an arm secured to said cross-plate in position to control its hinge, said arm having a 75 downturned rear end, a spring-controlled trigger-lever hinged to the truck-frame and having a pin bearing above said arm and seated normally against a shoulder thereon, whereby the apron is held up in normal position, and the front trigger-guard and connections for swinging the trigger-lever to carry its pin free of the arm which is thereby released and rises with its downturned rear end bearing against the pin, whereby the apron 85 is dropped to rest its foot on the road-bed and is there held.

5. A car-fender consisting of an apron the 90 foot of which is carried normally above the road-bed, a cross-plate back of said apron and 95 hinged at its lower edge to a beam of the truck-frame, downwardly and backwardly extending arms connecting the head of the apron with the cross-plate, an arm secured to the upper edge of the cross-plate and extending rearwardly and means for holding and releasing said arm to control the hinged cross-plate, and to hold the apron in its normal position and to drop it, to rest its foot on the road-bed.

6. A car-fender consisting of an apron, the 100 foot of which is carried normally above the road-bed, a cross-plate back of said apron and hinged at its lower edge to a beam of the frame, downwardly and backwardly extending carrying-arms connecting the head of the apron with the cross-plate, an arm secured to the upper edge of the cross-plate and extending rearwardly, a swinging trigger-lever with a pin bearing on the arm to hold it, and 105 means for operating the trigger-lever to release the arm, whereby the apron is released to drop its foot to the road-bed.

7. A car-fender consisting of an apron, the 110 road-bed, a cross-plate back of said apron and hinged at its lower edge to a beam of the truck-frame, downwardly and backwardly extending arms connecting the head of the apron with the cross-plate, an arm secured to 115 the upper edge of the cross-plate and extending rearwardly, said arm having a downturned rear end, a spring-controlled trigger-lever hinged to the truck-frame and having a pin bearing above said arm and seated normally against a shoulder thereon, whereby the apron is held up in normal position, and means for swinging the trigger-lever to carry its pin free of the arm which is thereby released and rises with its downturned rear end 120 bearing against the pin, whereby the apron 125 is dropped to rest its foot on the road-bed and is there held.

8. A car-fender consisting of an apron, the

foot of which is carried normally above the road-bed, a cross-plate back of said apron and hinged at its lower edge to a beam of the truck-frame, downwardly and backwardly 5 extending arms connecting the head of the apron with the cross-plate, an arm secured to the upper edge of the cross-plate and extending rearwardly, said arm having a downturned rear end, a spring-controlled trigger-lever hinged to the truck-frame and having 10 a pin bearing above said arm and seated normally against a shoulder thereon, whereby the apron is held up in normal position, and the front trigger-guard and connections for 15 swinging the trigger-lever to carry its pin free of the arm which is thereby released and rises with its downturned rear end bearing against the pin, whereby the apron is dropped to rest its foot on the road-bed and is there 20 held.

9. A car-fender consisting of an apron composed of a series of spring-rods bent to form a scoop and having their upper ends secured to a common head, arms hinged to said head, 25 and springs to hold the apron up with its foot normally above the road-bed, a cross-plate hinged to the truck-frame and to which the arms of the apron are secured, an arm secured to said cross-plate, a trigger-lever with a pin 30 to hold and release said arm and to permit the apron to drop its foot to the road-bed, and means for operating the trigger-lever.

10. A car-fender consisting of an apron

composed of a series of spring-rods bent to form a scoop and having their upper ends secured to a common head, arms hinged to said head, and springs to hold the apron up with its foot normally above the road-bed, a cross-plate hinged to the truck-frame and to which the arms of the apron are secured, an arm secured to said cross-plate, a trigger-lever with a pin to hold and release said arm and to permit the apron to drop its foot to the road-bed, and the front trigger-guard and connections for operating the trigger-lever. 35 40 45

11. In a car-fender, a cross-plate hingedly supported from the car, an apron hingedly supported at its upper end by said cross-plate, a spring for holding the foot of said apron normally above the road-bed, holding 50 means for said cross-plate, and means for releasing said holding means to drop said cross-plate and apron carried thereby.

12. A car-fender comprising an apron, a cross-plate hinged to the truck-frame, arms 55 secured to said cross-plate to which arms said apron is hinged, springs to hold the apron-foot yielding above the road-bed, an arm secured to said cross-plate, a trigger-lever to hold and release said arm, and means for operating the trigger-lever. 60

In witness whereof I hereunto set my hand.

GEORGE WILLARD DOUGLAS.
